UNITED STATES PATENT OFFICE.

CORNELIA J. GRAY, OF CHICAGO, ILLINOIS.

DESIGN FOR A DUST-PAN.

SPECIFICATION forming part of Design No. 85,530, dated December 31, 1901.

Application filed November 14, 1901. Serial No. 82,325. Term of patent 3½ years.

To all whom it may concern:

Be it known that I, CORNELIA J. GRAY, a citizen of the United States, residing at Chicago, in the county of Cook and State of Illinois, (whose post-office address is the city of Chicago,) have invented and produced a new and original Design for Dust-Pans, of which the following is a specification, reference being had to the accompanying drawings, forming part thereof.

My invention consists of the new shape or configuration of dust-pan shown in the drawings and hereinafter described.

My invention is illustrated in the accompanying drawings, in which—

Figure 1 is a plan view, and Fig. 2 a longitudinal section, of the dust-pan.

Referring to the drawings, the design comprises the configuration of the dust-pan A, as shown. It is provided with the front inclined smooth dust-receiving portion B, which has the beveled edge C and slopes upwardly from said edges to about the median line of the dust-pan, where it joins at a sharp oblique angle the vertical front wall of a rectangular well or depression portion E. The walls of this well are straight and vertical, and its

rear wall forms the rear end of the dust-pan. The well has a flat bottom. The well extends back from about the median line of the 30 dust-pan to the rear end thereof. The dust-pan has vertical inclosing sides, which are outwardly curved toward the front end. At its rear end it is provided with a handle F.

The leading feature of my design consists 35 of the shape of the dust-pan, as shown, provided with the front smooth inclined dust-receiving portion extending to about the median line of the pan and the rectangular well extending from the termination of said inclined portion to the rear end of the dust-pan and having straight vertical walls and a flat bottom.

Having thus described my invention, what I claim is—

The design for a dust-pan substantially as herein shown and described.

In testimony whereof I have hereunto affixed my signature in the presence of the two subscribing witnesses.

CORNELIA J. GRAY.
